AIR TRANSLATING APPARATUS

Gustav H. Koch, Springfield, Mass., assignor to
Westinghouse Electric Corporation, East Pitts-
burgh, Pa., a corporation of Pennsylvania

Application August 14, 1947, Serial No. 768,686

14 Claims. (Cl. 230—274)

1 This invention relates to air translating apparatus and, more particularly, to a fan of the propeller type.

In operation of a propeller fan of the type employed to effect movement of air in a generally axial direction, I have found that a substantial portion of the intake air is drawn radially inwardly toward the propeller blades, due to the creation of suction or low pressure in the region outwardly of the blade tip annulus. The direction of flow of this inwardly-flowing air must be changed upon its introduction into the main axially-flowing stream at the fan blades. Not only is the velocity of such radially-flowing air thereby reduced, but reaction thereof with the air flowing from the region rearwardly of the propeller promotes an undesirable choking or turbulent effect which I have found reduces the flow of air from the rear or suction side of the propeller and thereby limits the capacity of the fan. It is herein proposed to devise means for initially effecting the necessary change in direction of air drawn from the region laterally of the fan, and for facilitating forward movement of this air in a path parallel to that of the main axial stream.

I have discovered that a marked advance in efficiency and capacity of such a fan may be attained by provision of means effective to deflect the radially inwardly flowing air away from the fan blade operating zone, by turning such air into the axial direction before it reaches the blade operating zone, so that it will not choke off the axial air from the rear. More particularly, I propose to provide a shroud assembly comprising a series of deflector rings encircling the fan, each ring being curved from a rear peripheral edge, in cross section substantially tangent to a plane normal to the fan axis, to a forward annular discharge edge pointed in a direction parallel to the fan axis. With each such shroud ring disposed with its innermost edge located radially outwardly of the blade tip annulus, the assembled shroud structure becomes effective to change the direction of air flow from radially inward to the desired axially forward direction, and to cause such air to travel in an annulus which is disposed at least in part beyond the blade tip annulus. In other words, these shroud rings are adapted to move farther outwardly the flow annulus of air entering from the sides, for thereby increasing the flow area available for axially and forwardly moving air which enters the interior of the shroud assembly by way of the first or rear ring.

2 An important feature of the invention is the provision of a propeller type fan equipped with an annular shroud supported in coaxial encompassing relation with respect to the propeller and forming an annular space outwardly thereof, the shroud having spaced guiding surfaces constructed and arranged to effect an initial change in direction of air flowing from the lateral region prior to introduction of such air into the annular space for merger with air flowing axially from the region rearwardly of the fan.

Another object of the invention is the provision, in a motor-driven fan apparatus, of means for minimizing blade torque.

It is also an object of the invention to equip a motor-driven fan apparatus with means for increasing volumetric efficiency.

These and other objects and features of the invention will be apparent in the following more detailed description thereof, taken in connection with the accompanying drawings in which:

Figure 1 is an elevational side view, mainly in section, of a fan constructed in accordance with the invention;

Figure 2 is a perspective view of the fan shown in Figure 1;

Figure 3 is a diagrammatic view illustrating the approximate paths of air flow developed in the operation of an ordinary fan;

Figure 4 is a diagrammatic view illustrating the approximate paths of air flow developed in operation of a fan having associated therewith a shroud structure constructed in accordance with the invention;

Figure 5 is a diagrammatic view illustrating an improved fan apparatus embodying the invention in a different form; and

Figure 6 is an elevational view of a fan constructed in accordance with the invention and disposed in association with a window.

The term "propeller" is used herein to designate a fan of the axial flow or screw propeller type. The word "forwardly" is used to indicate the direction of air flow, or toward the discharge side, and the word "rearwardly" is used to designate the direction toward the suction side of the fan.

The "axial extent" of a member is its extent in a direction parallel to the axis; in other words, the distance between two planes which are normal to the axis and between which planes the member extends.

Operational characteristics of a conventional fan are illustrated schematically in Figure 3

of the drawings. It will be observed that in the case of an ordinary fan, a large proportion of the air drawn toward the propeller comes in at the sides. The direction of this air flowing inwardly from the lateral region must be changed by the propeller, which draws such air into the path of air flowing axially and forwardly. As a result, the main axial stream of air flowing from the region in back of the fan is subjected to undesired choking and turbulence, tending to absorb power and to limit the efficiency and capacity of this type of fan.

As shown in Figure 4, by equipping a fan unit with a series of annular vanes, or shroud members constituting a shroud assembly, in accordance with my invention as hereinafter more fully explained, a larger volume of air can be moved in paths as indicated by the arrows. A large proportion of the total volume of air moved by the propeller enters the blade circle from the side regions. This air flows over the curved shroud members, so that most of the incoming lateral air is subjected to an initial change in direction by the shroud rings and is subsequently carried forwardly, along with the main axially flowing body of air normally supplied from the region in back of the propeller. By reason of the clearance, between the propeller and the several shroud members of the assembly, this forwardly directed air, which initially entered from the sides, is introduced into a relatively unimpeded flow path, facilitating merger thereof with the main axially flowing air without appreciable turbulence.

In Fig. 5 the principle of the invention is further illustrated in the form of a fan and shroud construction which I believe approaches the ideal embodiment of my invention, although the form shown in Fig. 1 will be first described hereinafter as preferable from the standpoint of design and economical production standards. As shown in Fig. 5, a shroud assembly comprising a relatively large number of narrow rings of curved cross section and of graduated hoop diameter, increasing from back to front, are here provided to insure, with maximum efficiency, the desired initial change in direction of radially inwardly flowing air into an axial path, so that substantially no portion of such air will reach the blade operating zone. This air will be carried with the main axially flowing air stream, thus utilizing available energy that might otherwise be lost, as hereinafter explained.

Referring now to Fig. 1 of the drawings more in detail, the preferred type of fan assembly with which my invention may be associated includes an electrically driven fan unit, indicated generally by the reference character 11, which is suitably supported within the shroud assembly 12 by a U-shaped tubular frame section 13. The frame section 13 is carried on a floor standard or frame 16 of the adjustable type which may be similar to that disclosed in my Patent No. 2,521,920 assigned to the assignee of the present invention. The frame 16 is adapted to rest on the floor, and may be provided with rollers 17.

I prefer to utilize a single tubular member bent in the form of a U to provide the normally vertically disposed frame section 13, with the intermediate portion 14 thereof adapted to extend above the shroud assembly 12 containing fan 11, thus providing a convenient handle.

As is best shown in Figure 1 of the drawings, the fan unit 11 includes a motor 19 adapted to drive a propeller 20 which is mounted on the

motor shaft 21. According to the invention in the preferred form illustrated, the shroud assembly 12 surrounding the fan unit comprises a plurality of parallel shroud rings or annular vanes 22, 23, 24, 25 and 26, which are axially spaced apart and are supported on straps 27 carried by the frame section 13. The straps 27, preferably four in number, are arranged parallel to the longitudinal axis of the fan unit, which is supported therefrom by means of upper and lower brackets 28 having radially extending arm portions secured by bolts 29 to lugs which are welded to the respective straps. The intermediate portions of the brackets 28 may be riveted or otherwise secured to the motor housing 19.

Each of the shroud members 22, 23, 24, 25 and 26 may be rolled or otherwise formed from strip stock. Referring to Fig. 1 and to the shroud member 22 by way of example, it will be noted that the strip is rolled to provide a body having a portion *a* of arcuate cross section, and terminating in an end *b* of minimum diameter and an opposite end *c* of maximum diameter, the latter being further provided with an inverted annular roll or curl defining a shallow channel. In assembling the respective shroud members, the ends of each are brought together in spaced relation and spot welded to one surface of a joining strip 30. The joining strip 30 has an end 31 suitably curved to engage a surface of the arcuate position *c* of the shroud member 26, while the opposite end of the strip terminates adjacent the end *b* of the shroud member 22.

It will be understood that each of the straps 27 is spot welded to the adjacent portions *b* of the shroud members 22, 23, 24, 25 and 26. The straps 27 are slightly curved laterally to facilitate accurate engagement thereof with the several shroud members. As is best shown in Figure 1, a suitably formed aperture 33 is formed in one end of each of the straps 27, and is adapted to register with a similar opening formed in the adjacent portion of the shroud member 26, for receiving the vertically disposed tubular portions of the frame section 13. For securing the shroud assembly 12 in place with respect to the frame section 13, the adjoining surfaces, in the regions of the openings 33, are welded together.

As illustrated in Figure 1, the annular shroud members 22, 23, 24, 25 and 26 are disposed in concentric surrounding relation with respect to the propeller 20, with the first shroud member 22 located somewhat in advance or forwardly of the propeller, and with the shroud member 26 disposed rearwardly of the propeller. The shroud members are disposed in substantially continuous axial extent; that is, the axial extent of each shroud member extends substantially to and is substantially continuous with the axial extent of each adjacent shroud member, so that there is not substantial gap between the axial extents of adjacent shroud members. In the preferred embodiment shown, the respective shroud members are mounted in substantially non-overlapping relation with adjacent edges disposed in the same plane, and with the respective ends *b* thereof disposed forwardly of the arcuate portions *a* and the outer ends *c*. It will be noted that the inside surfaces of the respective shroud rings are spaced outwardly of the blade tips of the propeller 20, so that an annular flow passageway 35 is provided for facilitating unobstructed forward flow or air introduced from the lateral region and directed axially as already explained.

For closing the rear end of the shroud assembly 12, there is provided a disc-shaped screen 36 of wire mesh or other foraminated material which is initially formed with a diameter formed somewhat in excess of that of the channel *c* in the shroud member 26. To maintain the screen 36 in place, a suitable fixture (not shown) may be provided to distort the screen to a dished form, to enable a marginal portion thereof to be inserted into the channel *c*, so that upon release of the fixture the screen will spring into gripping relation with the shroud member as shown in Figure 1. An annular resilient channel member 37, made of a flexible material such as rubber, is preferably interposed between the channel *c* and the screen 36, and carries a flat marginal flange 38 which is adapted to overlie the outer portion of the screen.

For closing the other or front end of the shroud assembly 12 there is provided an annular grille support 39, on one end of which is formed an annular channel 40 similar to the channel *c* of the shroud member 22. This annular channel 40 is adapted to receive the outer edge of a wire mesh screen 41, which may be secured in place in the manner just explained with reference to the screen 36. The inner annular end of the grille support 39 has a diameter slightly less than the diameter of portion *b* of the shroud member 17, and is provided with an annular bead 42 which is adapted to be snapped into locking engagement with suitable embossed or raised portions formed on the respective straps 27 at points indicated by the reference character 43.

Operation

In operation, when the propeller 20 is rotated in the usual manner, a main supply of air is drawn from the rear of the fan through the screen 36, and is directed in an axially flowing stream by the moving blades of the propeller and thrust forwardly through the screen 41. At the same time, as indicated diagrammatically in Figure 4 of the drawings, air is drawn radially inwardly from the circumferential region surrounding the propeller 20 due to the suction created by the propeller, and impinges on the arcuate surfaces *a* of the respective shroud members forming part of the assembly 12. The air thus flowing inwardly from the region laterally of the propeller is thereby turned by the shroud members and directed forwardly at least partly through the passageway 35, thus flowing outwardly of the main axially flowing stream of air, without causing undue turbulence. Referring to Figure 4, it will be observed that not only is side air drawn radially inwardly and then directed forwardly by the shroud members adjacent and rearwardly of the propeller 20, by direct action thereof, but that this axially flowing stream is augmented by additional air drawn radially inwardly and given an axial direction by the shroud members 22 and 23 at points forwardly of the propeller. It has been observed that the suction created in the vicinity of the shroud members apparently tends to reach a maximum at the shroud members immediately behind and adjacent the propeller.

Although the dimensions of a fan apparatus constructed in accordance with my invention are not necessarily critical and are not to be understood as limiting the scope of the invention, I have found that remarkable results can be achieved with a construction in which a sixteen inch fan propeller is employed in association with

a shroud assembly comprising five shroud members substantially twenty inches in outside diameter. Each such shroud member having an inside diameter of seventeen inches may preferably be provided with an arcuate surface having both a cross-sectional radius and an axial depth of about one and one-half inches. Assuming that five similar shroud members are employed and mounted as hereinbefore described, the shroud assembly will thus measure approximately ten inches in depth, and will include an annular flow space 35 about one-half inch in width. I have found that a typical fan and shroud assembly embodying the invention can be operated to move air at the approximate rate of 3,000 cubic feet per minute, as compared with a rate of 2,300 cubic feet per minute to be expected with a similar fan not equipped with my improved shroud assembly.

It will be apparent that in addition to the main function of improving operational efficiency of the fan as hereinbefore explained, the shroud assembly 12 shown in the drawings constitutes a fan guard affording both protection and pleasing appearance. This fan apparatus, furthermore, is light enough to be readily portable and is operative to move a large volume of air with relation to its bulk and weight.

Although obviously having a wide range of utility, my improved fan is particularly adapted for household use and may provide a convenient and inexpensive means for ventilating and cooling the rooms of a small apartment or dwelling. As illustrated in Figure 6, the fan 11 will be highly efficient when placed about three feet from an open window *w* and operated to expel air from the interior to be cooled. Assuming that the fan is thus employed during a cool evening following a hot summer day, for example, and that the open window *w* has been selected with relation to other open windows in connected rooms, the entire volume of warm air in the interior of the dwelling can thereby be effectively supplanted by cool outdoor air in a relatively short time. As shown by the arrows in Figure 6, the volume of air drawn through the shroud assembly 2 and driven toward the window *w* will be augmented by air entrained from the region between the fan and window.

From the foregoing, the features of the fan 11a illustrated diagrammatically in Figure 5 and embodying the invention in a somewhat different form, will be readily understood. According to this form of the invention, a shroud assembly 12a comprising somewhat overlapping annular shroud members of successively greater diameters is provided, graduated in size from the largest shroud member 22a to the shroud member of minimum diameter 26a. The shroud member 22a, disposed forwardly of the propeller 15a, is in this case considerably larger in diameter than the shroud member 26a disposed at the opposite end of the assembly rearwardly of the propeller. The latter shroud member, however, preferably has a diameter at least as large as that of the propeller 20a, so that air impinging on the shroud rings is given a forward velocity without the direct help of the propeller and need not enter the propeller circle.

It will be noted that the annular flow passageway 35a, defined between the propeller and shroud members, is proportionately greater than the similar passageway 35 in Fig. 4, and diverges in the direction of air flow. Thus, air flowing

75 from the lateral region against the shroud mem-

ber 17a, for example, is turned forwardly into a flow path that is disposed radially outwardly of the forward path into which side air entering adjacent the shroud member 26a is directed. A relatively high degree of efficiency and increased capacity may thus be expected with a fan equipped with the shroud construction shown in Fig. 5 inasmuch as substantially all radially inwardly flowing air is turned and propelled forwardly without impeding the main axial stream, and without absorbing additional power from the fan blades and motor. Since the features of construction of a fan apparatus having the shroud assembly shown in Fig. 5 may otherwise be generally similar to those already described in connection with Fig. 1, it is deemed unnecessary herein to set forth a more detailed description.

While I have shown my invention in two forms, it will be obvious to those skilled in the art that it is not so limited, but is susceptible of various other changes and modifications without departing from the spirit thereof.

What I claim is:

1. An air translating device comprising a motor-driven propeller having a substantially unimpeded axial flow path both front and rear and adapted for intake and discharge of a main axially flowing stream of air, and a plurality of closely spaced shroud rings of curved cross section, each ring having a concave outer surface, an outer intake edge directed generally radially and an inner discharge edge of smaller diameter directed forwardly substantially parallel to the axis of the propeller, the discharge edge of each shroud ring extending forwardly substantially as far as the outer intake edge of the next shroud ring and having a diameter greater than that of said propeller, a plurality of said discharge edges being disposed adjacent the inlet side of said propeller, said shroud rings serving to introduce into the main axially flowing air stream, outwardly of the propeller operating zone, a continuous supply of air directed forwardly from the lateral region surrounding the propeller.

2. In an air translating device including a motor-driven propeller operative to draw air from both rearward and lateral regions for propulsion forwardly in an axially flowing stream, the combination therewith of annular shroud means having an inner diameter greater than the diameter of said propeller, and means for supporting said shroud means in coaxial encompassing relation with respect to said propeller, said shroud means having spaced guide surfaces curved transversely from radially inwardly to axially forwardly and arranged in axially spaced relation to effect initial change in direction of air flowing from said lateral region to an axially forward direction, prior to merger of such air with the air flowing axially from the region rearwardly of said propeller, said curved guide surfaces being disposed in substantially continuous axial extent with one thereof disposed rearwardly of said propeller and another thereof disposed at least partly within the axial extent of said propeller.

3. An air translating device comprising a motor-driven propeller and a shroud construction coaxially encompassing said propeller, said shroud construction comprising shroud members spaced to provide lateral passages for ingress of air initially approaching the tips of the propeller, each of said shroud members being trans-

versely curved inwardly and forwardly from its outer circumferential inlet edge to its inner circumferential discharge edge, said inner edge of each shroud member being disposed forwardly of the outer edge thereof in the direction of flow and extending forwardly substantially parallel to the axis of said propeller, the shroud members being substantially continuous in axial extent and the inner edge of at least one of said shroud members being disposed within the axial extent of said propeller and having an inside diameter greater than the diameter of the propeller to provide an annular passage therebetween, so that such radially inflowing air has its direction changed in said passages and issues therefrom with a large component of motion in the direction of flow from rear to front of the air translating device.

4. An air translating device comprising a motor-driven fan and a plurality of annular shroud members coaxially encompassing said fan, and spaced through a circumferential zone extending from a plane normal to the fan axis at the suction or inlet side of the fan to a plane normal to the fan axis at the discharge side, each shroud member having a concave outer surface which is transversely curved from a generally radially directed outer inlet edge to a substantially axially directed inner discharge edge, said inner edge of each shroud member being disposed forwardly of the outer edge thereof in the direction of flow through said fan and closely adjacent the plane of the outer edge of the next shroud member, said inner edge of each of said shroud members being substantially larger in diameter than said fan to provide an intervening annular space in which air introduced between said shroud members flows in an axial direction along with the main axially flowing stream of air propelled by said fan.

5. In an axial flow air translating device including a fan, a plurality of axially spaced shroud rings encompassing said fan at substantially all points from a plane normal to the fan axis at the inlet side of the fan to a parallel plane at the discharge side, each of said shroud rings having an inner circumferential discharge edge pointed substantially axially in the direction of air flow through the fan and being transversely curved rearwardly and outwardly to a rounded outer circumferential inlet edge portion extending in a substantially radial direction, said inner circumferential discharge edges of the shroud rings being spaced outwardly of the fan to provide an intervening annular space, so that air drawn radially inwardly between said outer annular edges of the shroud rings is initially turned into an axial path and then directed forwardly at least partly in said annular space along with the main axially flowing stream of air propelled by said fan.

6. In an axial flow air translating device including a fan, a plurality of axially spaced shroud rings encompassing said fan from a plane parallel to the fan at its suction side to a parallel plane at its discharge side, each of said shroud rings having an inner circumferential edge pointed substantially axially in the direction of air flow through the fan and being transversely curved rearwardly and outwardly to a circumferential portion terminating in a re-entrant or inwardly extending flange forming an inwardly open peripheral channel, and a disc-shaped inlet screen having its peripheral edge

removably engaged in said channel of the rear-most of said shroud rings.

7. In an axial flow air translating device including a propeller, a plurality of spaced shroud rings graduated in diameter and coaxially encompassing said propeller in outwardly spaced relation thereto, each of said shroud rings being transversely curved from a generally radially directed outer inlet edge to a substantially axially directed inner discharge edge, the inner edge of the smallest ring having a diameter at least as great as that of the propeller, said shroud rings being disposed in order of increasing diameter from a plane normal to the propeller axis at the suction or inlet side of the propeller to a parallel plane at the discharge side, with the inner edge of each shroud ring disposed forwardly of the outer edge thereof in the direction of flow through said air translating device and substantially in the plane of the outer edge of the next shroud ring, the inner edge of a plurality of said shroud rings being disposed as far rearwardly as the tip of the propeller, said shroud ring assemblage providing a substantially conical space outwardly of the propeller, so that air drawn radially inwardly thereby is initially turned by said shroud rings into an axial flow path and then directed forwardly in said conical space along with the main axially flowing stream of air propelled by the propeller.

8. An air translating device comprising a propeller, supporting means, and a plurality of annular vanes carried by said supporting means in surrounding concentric relation with respect to said propeller, said vanes having concave outer surfaces which are curved from generally radially inwardly to substantially axially forwardly, and the inner or discharge edges of a plurality of said vanes being disposed as far rearwardly as the tip of said propeller and the inner edge of one vane being disposed within the axial extent of said propeller, the inner edge of each vane extending forwardly substantially as far as the adjacent edge of the next vane, and the inside diameter of each vane that is disposed as far forwardly as the tip of said propeller being greater than the diameter of said propeller to provide an annular passage therebetween, said vanes serving to intercept and turn forwardly air flowing radially toward the propeller for flow along with the main air stream moved axially by the propeller.

9. An air translating device comprising a propeller and a series of annular vanes encompassing said propeller, each vane having a discharge edge directed forwardly substantially parallel to the axis of the propeller and of greater diameter than the propeller, each vane having an inlet edge of greater diameter than the discharge edge and disposed rearwardly of the discharge edge and substantially as far rearwardly as the radial plane of the discharge edge of the next vane, adjacent vanes providing passages for receiving air flowing from the lateral region toward the axis and for directing such air in a substantially axial direction to flow along with the main axially flowing stream of air, the outlet end of the passage between two of such vanes being disposed adjacent the suction side of the propeller.

10. In an air translating device having a propeller adapted to effect flow of a main axially flowing stream of air, the combination of a plurality of shroud ring elements each having a concave outer surface which is transversely curved from a generally radially directed circumferential inlet edge of maximum diameter to a sub-

stantially axially directed circumferential discharge edge of smaller diameter extending substantially parallel to the fan axis, the diameter of said discharge edge being greater than the diameter of said propeller, and means for supporting said shroud ring elements coaxially of said fan with the respective discharge edges of said elements pointed in the direction of axial flow and with the discharge edge of at least one of said shroud elements disposed within the axial extent of said propeller, said shroud ring elements being spaced apart with the discharge edge of each disposed substantially at a plane passing through the inlet edge of the adjacent element, whereby air drawn radially inwardly by said propeller is turned and directed forwardly and smoothly merged with the main axially flowing stream of air driven by said propeller.

11. Air translating apparatus as set forth in claim 10 wherein two of said shroud ring elements are disposed beyond the axial extent of said propeller on the suction or air inlet side thereof.

12. Air translating apparatus as set forth in claim 10 wherein the discharge edge of said one shroud ring element is disposed as far rearwardly as the tip of said propeller and wherein two other shroud ring elements are disposed on the suction or inlet side of said one shroud ring element.

13. In an air translating device having a propeller fan adapted to effect flow of a main axially flowing stream of air, the combination of a plurality of shroud ring elements each having an annular concave outer surface extending between an inlet edge of maximum diameter and a discharge edge of smaller diameter, the inside diameter of each shroud ring element being greater than the diameter of said propeller to provide an annular passage therebetween, said concave outer surface extending substantially parallel to the axis of said fan adjacent said discharge edge, and means for supporting said shroud ring elements concentrically of said fan with the respective discharge edges of said elements directed forwardly and with the discharge edge of at least one of said shroud elements disposed within the axial extent of said fan, adjacent shroud ring elements being axially spaced, the discharge edge of each shroud ring element extending substantially as far forwardly as the inlet edge of the next shroud ring element, for directing forwardly and along with the axially flowing air stream all the air that is drawn radially inwardly between adjacent shroud ring elements from the lateral regions surrounding said fan.

14. A guard assembly for an electric fan having a propeller, comprising a series of annular concave shroud members of different diameters with the smallest shroud member having an inside diameter at least equal to that of said propeller and being arranged in order of increasing diameter in the direction of air flow, and mounting means for supporting said series of shroud members coaxially of said propeller, each of said shroud members being transversely curved inwardly from an outwardly directed peripheral inlet edge to a forwardly directed inner discharge edge to effect change in direction of air initially flowing radially inwardly toward said propeller to an axially forward direction, prior to merger of such air with air flowing axially from the region rearwardly of said propeller, the inner edge of at least one shroud member being disposed within the axial extent of said propeller and sub-

11

stantially as far forwardly as the inlet edge of the next shroud member.
